FIG. 1

FIG. 4

FIG. 2

FIG. 3

FIG. 6

FIG. 5

FIG. 1 is a perspective view of an ear plug unit showing our new design;

FIG. 2 is a front elevational view of one end of the ear plug unit, the remainder of the unit being omitted for convenience of illustration;

FIG. 3 is a right side elevational view of FIG. 2;

FIG. 4 is a left side elevational view of FIG. 2;

FIG. 5 is a rear elevational view of FIG. 2; and

FIG. 6 is a top plan view of FIG. 2.

The end of the ear plug unit not shown in FIGS. 2, 3, 4, 5 and 6 is understood to be a mirror image thereof.

We claim:

The ornamental design for an ear plug unit, substantially as shown and described.
